UNITED STATES PATENT OFFICE.

LOUIS A. MARKS, OF NEW YORK, N. Y.

DESIGN FOR WOVEN FABRIC.

SPECIFICATION forming part of Design No. 23,792, dated November 18, 1894.

Application filed September 20, 1894. Serial No. 523,532. Term of patent 3½ years.

To all whom it may concern:

Be it known that I, LOUIS A. MARKS, a citizen of the United States, residing at New York, in the county of New York and State of New York, have invented and produced a new and original Design for Woven Fabrics; and I do hereby declare the following to be a full, clear, and exact description of the same, reference being had to the accompanying drawing, forming a part thereof.

This invention relates to a new and original design for woven fabric to be used with such colors as may be desired and it consists in the peculiar design as shown in the accompanying drawing, wherein A designates the body, and B a stripe of alternating clusters of heavy

and light bars. Midway between the stripes B and alternating therewith are stripes C composed of short parallel bars extending horizontally.

The essential features are the body with the alternating stripes B and C.

What I claim as new, and desire to secure by Letters Patent, is—

The design for woven fabric substantially as shown and described.

In testimony whereof I affix my signature in presence of two witnesses.

LOUIS A. MARKS.

Witnesses:

L. S. BACON,
J. ROSS COLHOUN.
